FILLING WOUND BOBBIN.

Application filed May 25, 1926. Serial No. 111,651.

This invention relates to filling wound bobbins and more particularly to filling wound bobbins used in looms in connection with side slipping feelers.

- 5 In looms of the automatic or filling replenishing type it is now the general practice to provide feeler mechanisms which upon substantial exhaustion of the filling in the shuttle will initiate the operation of 10 the replenishing mechanism before the filling in the shuttle is completely exhausted. Any filling remaining on the filling carrier when it is ejected from the shuttle constitutes waste, and many attempts have been 15 made heretofore to minimize such waste, either by the use of different types of feeler mechanisms or by providing the filling carriers or bobbins with a reserve supply of filling or "bunch", so that upon withdrawal 20 of the service windings from the bobbin, the feeler mechanism will call for a change of filling before complete exhaustion thereof in the running shuttle.

- Where "bunches" have heretofore been 25 used, it has been the common practice to provide a feeler mechanism which will cooperate with the "bunch" on the filling carrier and call for a change of filling before the "bunch" has been entirely depleted. 30 In some cases, also, it has been proposed to provide filling carriers with a "bunch" to cooperate with a side slipping feeler, and such side slipping feeler has at times been arranged to contact with the "bunch" on 35 the filling carrier or bobbin and at other times to engage the regular service windings on the filling carrier until the "bunch" has been reached. The action of the feeler when of the side slipping type is to exert a 40 stress or push upon the filling on a detecting beat, with the result that where the feeler cooperates with the service windings, such windings become disarranged on the filling carrier or bobbin, or "slough". Where 45 this occurs, the filling will frequently become loose and snarl or kink as the shuttle is picked and cause breakage of filling. Where the filling is of a slippery nature, such, for instance, as rayon or artificial silk, 50 this sloughing action of the filling under the stress of the side slipping feeler becomes emphasized, and frequent snarls and breakages result.

One of the objects of the present invention is to provide a filling wound bobbin wherein the difficulties heretofore experienced in connection with a side slipping feeler are overcome, and sloughing or displacement of the yarn by the side slipping feeler is obviated. In accordance with the present invention, the filling carrier or bobbin is provided with a head and a cylindrical "feeler step" portion which merges into a tipwardly extending tapering portion, and on such filling carrier or bobbin the present invention provides a "bunch" of filling adjacent the head of the bobbin, a plurality of feeler engaging filling wound upon the feeler step portion and an initial service winding which overlies the feeler step windings and extends tipward beyond the end thereof, the result being that when the service windings have been withdrawn from the filling carrier or bobbin, to expose the feeler step windings, the feeler will be held from side slipping movement by the feeler step windings on a detecting beat, without causing the yarn to slough or snarl or become loose under the stress of the feeler, and when the feeler step windings have been withdrawn from the filling carrier or bobbin, the feeler may side slip, leaving on the filling carrier or bobbin as wastage only the small amount of yarn remaining in the bunch.

In accordance with the preferred form of the invention, the "bunch" is wound upon the bobbin adjacent the head with minimum or no traverse, so that the coils of yarn lie close together, and the feeler step windings are wound upon the cylindrical portion of the bobbin with a longer traverse than that of the "bunch", so that the windings on the feeler step portion of the bobbin are more separated than in the "bunch" windings, while the initial service winding extends from the "bunch" beyond the tipward end of the cylindrical feeler step windings.

The invention will best be made clear from the following description and the accompanying drawings of one good form thereof.

In the drawings:

Fig. 1 is a plan view with parts broken away, showing the filling carrier or bobbin in a shuttle embodying the present invention.

tion and employed in connection with a side slipping feeler;

Fig. 2 is an enlarged or exaggerated sectional elevation of a filling carrier or bobbin 5 having the filling wound thereon in accordance with the present invention;

Fig. 3 shows the action of the feeler upon the feeler step windings when the service windings have been fully withdrawn from 10 the bobbin; and

Fig. 4 is a similar view with parts broken away showing the feeler step windings as having been withdrawn from the bobbin and freeing the feeler to its side swipe 15 movement.

The present invention is more particularly intended for use in connection with a side slipping feeler, and while such type of feeler may be of any usual character, a simple 20 and efficient form of such side slipping feeler is herein shown, but the invention is not to be regarded as restricted thereto.

In accordance with the invention, the shuttle 1 may be of the usual filling feeler 25 type provided with bobbin holding jaws 2 between which the bobbin head 3 is held when the filling carrier or bobbin 4 is within the shuttle. In the present instance, the head 3 of the bobbin is shown as provided 30 with three rings 5 for engagement by the bobbin holding jaws, but obviously, any such number of rings may be employed as desired. As usual in this type of shuttle, the front wall of the shuttle is provided 35 with an opening 6 through which the feeler 7 may pass to feel for the filling on a detecting beat of the lay.

In the present instance of the invention, the side slipping feeler comprises the rearwardly extending feeler member 7 having 40 teeth 8 at its rear end portion, which, when the service windings have been withdrawn from the bobbin, engage the feeler step windings, as will more fully appear herein-after. The feeler member 7 is supported 45 by the feeler stand 9 which may be secured to the loom frame, as usual, and the feeler has the lateral extension 10 to which is secured one end of a spring 11, the other end 50 of which is connected to the feeler stand at 12 to normally exert a pulling effect to move the feeler rearwardly. The laterally extending arm 10 has a toe portion 13 which, when the feeler is in its rearward feeling 55 position, is adapted to engage a stop 14 secured to or forming part of the feeler stand. Extending through an opening 15 in the feeler stand is the transmitter 16 which, upon side slipping movement of the feeler, 60 is moved lengthwise to initiate replenishment of filling. The rearwardly extending arm of the feeler 7 is adapted to engage a stop 17 on the feeler stand when the feeler is in its rearward feeling position, to thereby 65 position the feeler. The feeler mechan-

ism forms no essential part of the present invention except to the extent that it is a side slipping feeler which effects replenishment of filling by side slipping movement when the filling is to be changed, and the 70 particular construction of the feeler mechanism herein described may be varied indefinitely or any other type of side slipping feeler may be employed.

The filling carrier or bobbin 4, as herein 75 before described, has the head portion 3 and a cylindrical feeler step portion 18 which extends from the head 3 towards the tip of the bobbin, and at a substantial distance from said head, as at 19, the cylindrical portion merges into a tapering portion 20 which 80 extends towards the tip of the bobbin.

In accordance with the present invention, the bobbin 4 is provided with a "bunch" 21 adjacent the head of the bobbin, and as the 85 amount of filling in the "bunch" is to constitute waste when the bobbin is ejected from the shuttle, the length of filling in the "bunch" may be regulated so as to insure a final full pick of filling on the last pick of 90 the shuttle prior to replenishment. The "bunch" is wound upon the filling carrier or bobbin with little or no traverse, with the result that the windings of filling constituting the "bunch" lie close together and 95 form a compact mass, as indicated in Fig. 1.

The feeler step portion of the bobbin is substantially cylindrical, and as indicated in Fig. 2, extends longitudinally of the bobbin from a point *a* adjacent the "bunch" 21 to a point *b*, slightly nearer the head of the bobbin than the point 19 where the cylindrical feeler step portion merges into the tapering portion 20 of the bobbin. On the cylindrical step portion 18 of the bobbin a 100 series of feeler step windings 22 are placed between the "bunch" 21 and the point 19 where the cylindrical feeler step portion merges into the tapering portion of the bobbin. The traverse of the filling on the feeler 105 step portion is greater than the traverse of the filling in the "bunch" portion 21, with the result that the coils of filling wound upon the feeler step portion 18 of the bobbin are more separated than in the "bunch" 110 21, to thereby afford proper holding conditions for engagement by the teeth 8 of the feeler.

Overlying the feeler step windings 22 is the initial service winding 23 of filling, and as will be noticed more particularly in Fig. 2, such initial service winding commences adjacent the "bunch" 21, approximately at *a*, and continues in a single traverse beyond the tip end portion *b* of the feeler step windings 22, as indicated in Fig. 2. In the windings illustrated in Fig. 2, the initial service winding extends not only beyond the end of the feeler step windings 23 at *b* but may if desired continue along to the inclined 115 230

portion of the bobbin beyond the point 19 where the cylindrical portion merges into the tapering portion of the bobbin, although this is not always essential.

- 5 When the service windings have been withdrawn from the bobbin to expose the feeler step windings 22, the toothed end portion of the feeler will act upon the feeler step windings and be held thereby from 10 side slipping movement. Since the feeler step windings 22 are confined to the cylindrical portion of the feeler step, the side stress of the feeler upon the feeler step windings will not effect any sloughing of 15 the yarn, which may then be withdrawn from the feeler step windings during the subsequent picks of the shuttle, as indicated in Fig. 3. When the windings on the feeler step 22 have been depleted, substantially as 20 indicated in Fig. 4, the feeler is freed to its side slipping movement and the filling is then leading to the "bunch" 21 which supplies the requisite amount for insuring a full pick of filling on the last flight of 25 the shuttle preceding replenishment.

It will be obvious from the filling wound bobbin herein described as an embodiment of the present invention that even with slippery yarn, such as rayon or artificial silk, 30 the side slipping feeler will not cause sloughing or displacement of the yarn due to the stress of the feeler upon the feeler step windings, which are confined substantially to the cylindrical feeler step.

35 This nonsloughing condition of the yarn is of particular importance and enables the feeler to act upon the feeler step windings at a point close to the tip end portion thereof, as indicated in Fig. 1, so that should 40 the shuttle rebound in the detecting box, the feeler will nevertheless feel upon the feeler step windings and not engage the shuttle spring as is liable to happen when the feeler acts closer to the head of the 45 bobbin.

What is claimed is:

1. A filling wound bobbin for use with 50 a side slipping feeler having a head, a substantially cylindrical feeler step portion and a tapering portion extending towards the

tip of the bobbin, a bunch of filling having a minimum separation of winding adjacent the bobbin head, feeler engaging filling wound upon the cylindrical feeler step portion with longer traverse than the bunch 55 windings, and an initial service wind overlying and extending tipward beyond the feeler step wind that the windings on the feeler step may hold the feeler from side slipping movement without sloughing the 60 filling until substantial depletion thereof after the service windings have been withdrawn from the bobbin.

2. A filling wound bobbin for use with a side slipping feeler having a head, a feeler 65 step portion and a tapering portion merging into the feeler step portion, a bunch of reserve filling wound upon the bobbin adjacent the head, a plurality of layers of feeler engaging filling wound upon the feeler 70 step portion with a longer traverse than the bunch, and a service wind of longer traverse than the feeler step wind overlying the feeler step wind and extending onto the tapering portion of the bobbin beyond the feeler step 75 wind that the stress of the feeler may be held by the feeler step wind until depletion thereof without sloughing the filling after the service wind has been withdrawn from 80 the bobbin.

3. A filling wound bobbin for use with a side slipping feeler having a head, a cylindrical feeler step and a tapering portion extending towards the tip of the bobbin, a non-feeler-engaging bunch which constitutes 85 waste, a plurality of feeler engaging layers of longer traverse than the bunch wound upon the cylindrical feeler step to hold the feeler from side slipping movement when they engage the feeler, and an initial service 90 layer of filling wound upon the bobbin on the tapering portion beyond the feeler step windings that the filling may be withdrawn from the bobbin without sloughing under the stress of the side slipping feeler. 95

In testimony whereof, we have signed our names to this specification.
